UNITED STATES PATENT OFFICE

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY

STEAM BOILER

Application filed September 14, 1923, Serial No. 662,621. Renewed May 1, 1928.

My present invention relates to steam boilers particularly of the type adapted for operation at high pressures and will be best understood from the following description and the 5 annexed drawings, in which Fig. 1 is a vertical section of a boiler embodying my present invention; Fig. 2 is an enlarged view of a pair of headers which may be used in the boiler shown in Fig. 1; Fig. 3 is a view similar 10 to Fig. 2 showing a modification; Fig. 4 is a section on the line 4—4 of Fig. 3; Fig. 5 is a section on the line 5—5 of Fig. 2; Fig. 6 is a section on the line 6—6 of Fig. 2; Fig. 7 is an 15 elevation of a part of a pair of headers showing still another modification; Fig. 8 is a section on the line 8—8 of Fig. 7; Fig. 9 is a section on the line 9—9 of Fig. 11; Fig. 10 is a section on the line 10—10 of Fig. 9, and 20 Fig. 11 is an elevation of a pair of headers, such as is shown in Figs. 2 and 3, showing a method of closing the space between them.

Like reference characters indicate like parts in the several views.

In the illustrative form of boiler shown in 25 Fig. 1, the water tubes 10 are divided into two banks, the high ends of the water tubes being connected to uptake headers 11 and the downtake headers 12 being divided into two parts connected by nipples 13. The two 30 lowermost rows of tubes 14 and 15 are of larger diameter than the tubes 10. Between the banks of water tubes is a superheater 16, a baffle 17 extending transversely of the water tubes to give the gases two passes across the 35 water tubes and directing the gases to the spaces between the nipples 13 and to a gas outlet 14^a leading to the upper end of an economizer 15^a, from the lower end of which the gases pass to a flue 16. The transverse 40 baffle 17 terminates at an inclined baffle formed adjacent the superheater headers and ending adjacent the downtake headers 12. A forced blast chain grate stoker 18 is located 45 beneath the furnace chamber 19. The downtake headers 12 are connected to a transverse steam and water drum 20 and the uptake headers 11 are similarly connected through the pipes 21. The drum 20 exemplifies a 50 steam and water separator which may be either the single compartment illustrated or

may also include a plurality of compartments. The connections between the separator and the end portions of the headers may be the direct form of connection shown, or may be made through intermediate compartments if 55 desired. The entire arrangement of boiler elements described above, forms a unit, by which term I mean a self-contained boiler forming either a part or all of the steam generating surface to which heat is applied. 60

It will be understood that the uptake and downtake headers are formed in a similar manner, so that a description of one of them will be sufficient. Preferably, in order to stand the high pressures for which the illustrative boiler is particularly adapted, I form the headers as seamless tubes, these tubes preferably having a curved perimeter with one part of such perimeter curved on a relatively long radius so as to give a somewhat flattened 70 portion in which the water tubes may be entered. In the specific form illustrated, the headers are substantially circular in cross-section for the greater portion of their circumference, the portion formed with the long 75 radius intersecting the circular outline of the header. It will be obvious that such a section is capable of standing heavy internal pressures, and, at the same time, provides a convenient tube surface so that the tubes may 80 enter the surface in groups with the tubes normal to such surface or very nearly so without undue bending of the ends of the tubes.

The tubes are preferably arranged in horizontal rows, as is usual in water tube boilers, 85 and preferably a plurality of the tubes of each row enter each header. The headers are preferably spaced apart a distance at least as great as the diameter of a water tube, in order that a tube may be withdrawn between the headers. By bending the ends of some or all of the tubes as shown best in Fig. 6, the tubes may be spaced across the boiler uniformly notwithstanding the space between the headers and, moreover, by bending the ends as shown in Fig. 6, the tubes in succeeding rows vertically may be staggered relatively to each other. While the arrangement shown in Fig. 2 does not produce uniform diagonal lanes between the 95 100

tubes as is usual in water tube boilers, such true and uniform diagonals may be obtained by slightly changing the vertical distances of the rows, if desired.

5 It is necessary to provide the headers with handhole openings which may be closed in the usual manner with fittings having internal seats, these holes being provided so that tube cleaners may be inserted in the 10 several tubes. In order not to weaken the header unduly, it is desirable that there shall be as few of these handholes as possible and that they be as small as possible, and for this reason, I preferably arrange the horizontal 15 rows of tubes in pairs in which the vertical distance between the rows in each pair is less than the vertical distance between the respective pairs. By this means, as shown in Fig. 2, for instance, a small circular hand- 20 hole 22 may be utilized to insert a cleaning tool in any one of the six tubes adjacent such handholes, and by bringing the rows of tubes adjacent the handholes 22 relatively close together, access to each of this group 25 of tubes may be had through a much smaller hole than would otherwise be possible. Since, however, it is not possible to enter a circular fitting through a circular hole, if such fitting is to be seated internally 30 of the header, I elongate some of the handholes, as shown, for instance, at 23 and, of course, provide a correspondingly elongated handhole fitting for such holes. As is well known, a fitting of this shape may be entered, such an elongated hole even though 35 it is to be seated on the interior of the header and by providing these elongated handholes adjacent each circular handhole, I am enabled to enter the fitting for the next ad- 40 jacent circular handhole through one of the elongated holes 23, the elongated hole being sufficiently close to the circular hole to permit a circular fitting to be passed through the elongated hole and then have its end 45 passed out through the circular opening.

With the tubes arranged as shown in Fig. 2, the middle tube of each group of three cannot be removed and replaced without also cutting out and replacing one of the adjacent tubes, because there is not sufficient distance between the rows to enable such middle tube to be passed between rows and then out between the headers. This difficulty may be obviated by arranging the rows as shown in Fig. 3, in which the vertical space between each adjacent pair of rows is at least as great as the diameter of one of the tubes. With such an arrangement, a middle tube of the group of three may be cut out and then raised 60 and passed over its adjacent tube in the same row to the space between the headers.

When the tubes are removed, they must be angled somewhat in order to pass the end through the space between the headers. The 65 tubes being small, the ends may be bent in

this angling without materially disturbing the baffle 17 through which the tubes pass. Preferably I make the space around the tube in the baffle 17 somewhat larger than the diameter of the tube to assist in this angling. 7 By having a single baffle, it is obvious that a tube hole through the baffle need be only slightly larger than the tube diameter and, moreover, by having a single baffle, the possibility of gas leakage through the tube hole in 7 the baffle is reduced to a minimum, because the transverse baffle acts merely as a guide to direct the gases, the pressures on the opposite sides of the baffle being such that the gases have little or no tendency to flow through the small openings in the baffle. The gases in the first pass tend to rise rather than to flow laterally, because of the stack effect of this first pass, and the suction in the second pass near the bottom of the baffle may be less at the lighter loads than the suction on the opposite side of the baffle in the first pass. Even at the higher loads, the suction in the second pass is not sufficiently greater than that in the first pass to draw any material amount of gases through the small openings around the tubes in the baffle.

The two lowermost rows of tubes 14 and 15 may be spaced either as shown in Fig. 2 or in Fig. 3. In the latter figure, the lowermost row is composed of a single tube for each header and the tubes of the row 15 are entered in groups of two in each header. This provides a very wide space between the tubes 14 of the lowermost row and a less space between the tubes 15 of the second row. In the arrangement shown in Fig. 2, the spacing between the rows of tubes 14 and 15 is uniform, the tubes in each row being entered singly and in pairs in adjacent headers. If desired, as shown in Fig. 2, some of the small tubes 10 may be arranged in a manner similar to the rows 14 and 15 of Fig. 2.

In Figs. 7 and 8, I have shown an arrangement in which the headers 11' are circular in cross-section and spaced apart at least the diameter of a tube with the tubes 10' having their ends bent alternatively in opposite directions in successive rows vertically so as to stagger the tubes, handhole fittings 24 being provided for openings opposite the ends of each tube. In the arrangement shown in Figs. 7 and 8, the tubes of a row do not extend across the space between a pair of tubes of adjacent rows.

Since the headers are spaced apart, it is desirable to close this space, and in Figs. 9, 10 and 11, I have shown a means to that end. In the form illustrated, lugs 25 are formed on the header, as, for instance, by autogenous welding, each lug being provided with a vertical slit 26 extending part way down through the lug and in each slit is positioned a projection 27 on the edge of a plate 28 spanning the space between the headers, this

plate preferably being curved as shown best in Fig. 9, so that its edges contact with the walls of the headers, and, at the same time, so that slight relative movement between the 5 headers will not jam the plate 28, the curved edges of the plate in such case sliding around the curved wall of the header.

Preferably the closure is formed of a plurality of plates 28 placed end to end with 0 their ends overlapping and each plate supported on the bottom of a pair of lugs 25. Preferably each plate 28 is provided with an opening through which cleaning tools may be inserted, this opening being closed in the 5 form illustrated by a slide plate 29 held against plate 28 by a pair of guides 30.

It will be understood that the arrangement shown in the drawings is merely illustrative and that the embodiment of my invention may be widely varied. Certain features and forms of this invention are not claimed herein, but are reserved for further divisional applications.

I claim:

1. A water tube boiler, having horizontally inclined water tubes connected at their ends to uptake and downtake headers, respectively, each header having a cross section whose perimeter is curved and the front part adjacent the tubes having a radius of curvature that is longer than the radius of curvature of the back part of said header, the tubes being arranged in horizontal rows with a plurality of tubes in each row entering the front 5 part of each header perpendicular to the surface thereof.
2. A water tube boiler, having horizontally inclined water tubes connected at their ends to uptake and downtake headers, respectively, each header having a cross section whose perimeter is curved and the front part adjacent the tubes having a radius of curvature that is longer than the radius of curvature of the back part of said header, the tubes being 5 arranged in horizontal rows with a plurality of tubes in each row entering the front part of each header, and the ends of the tubes being bent to stagger the tubes in adjacent rows vertically.
3. A water tube boiler, having horizontally inclined water tubes connected at their ends to uptake and downtake headers, respectively, each header having a cross section whose perimeter is curved and the front part 5 adjacent the tubes having a relatively long radius of curvature, the tubes being arranged in horizontal rows with a plurality of tubes in each row entering the front part of each header, said headers being spaced apart a distance at least as great as the diameter of a tube and the ends of the tubes being bent to space the tubes in each row uniformly across the boiler.
4. A water tube boiler, having horizontally 5 inclined water tubes connected at their ends

to uptake and downtake headers respectively, each header having a cross section whose perimeter is curved and the front part adjacent the tubes having a relatively long radius of curvature, the tubes being arranged 70 in horizontal rows with a plurality of tubes in each row entering the front part of each header, said headers being spaced apart a distance at least as great as the diameter of a tube and the ends of the tubes being bent 75 to space the tubes in each row uniformly across the boiler and to stagger all of the tubes in each row in relation to the adjacent rows vertically.

5. A water tube boiler, having horizontally inclined water tubes connected at their ends to uptake and downtake headers, respectively, each header having a cross section whose perimeter is curved and the front part adjacent the tubes having a relatively long 80 radius of curvature, the tubes being arranged in horizontal rows with a plurality of the lowermost rows formed of tubes of larger diameter than the remainder of the rows, a plurality of the tubes in each row of smaller 90 diameter entering the front part of each header perpendicular to the surface thereof.

6. A water tube boiler, having horizontally inclined water tubes connected at their ends to uptake and downtake headers, respectively, the tubes being arranged in horizontal rows with a plurality of tubes in each row entering each header, and the horizontal rows being arranged in pairs vertically and said pairs, being spaced apart vertically a 100 distance of at least a diameter of the tube.

7. A water tube boiler, having horizontally inclined water tubes connected at their ends to uptake and downtake headers, respectively, the tubes being arranged in horizontal rows with a plurality of tubes in each row entering each header, and the horizontal rows being arranged in pairs vertically with the vertical distance between the pairs of rows greater than between the rows of a pair.

8. A water tube boiler, having horizontally inclined water tubes connected at their ends to uptake and downtake headers, respectively, the tubes being arranged in horizontal rows with a plurality of tubes in each row entering each header, and the horizontal rows being arranged in pairs vertically with the vertical distance between the pairs of rows greater than between the rows of a pair, each header having a handhole opposite the ends of the tubes of each pair of rows entering such header, some of said handholes being circular and the remainder elongated with the long axis vertical, each circular hole having an elongated hole adjacent it.

9. A water tube boiler, having horizontally inclined water tubes connected at their ends to uptake and downtake headers, respectively, the tubes being arranged in horizontal rows and the headers being spaced apart a 120

- distance at least as great as the diameter of a tube, a plurality of tubes in each row entering each header and the ends of the tubes being bent to space the tubes in each row uniformly across the boiler.
- 5 10. A water tube boiler, having horizontally inclined water tubes connected at their ends to uptake and downtake headers, respectively, the tubes being arranged in horizontal rows and the headers being spaced apart a distance at least as great as the diameter of a tube, a plurality of tubes in each row entering each header and the ends of the tubes being bent to space the tubes in each row uniformly across the boiler and to stagger all of the tubes in each row in relation to the adjacent rows vertically.
- 10 15. A water tube boiler, having horizontally inclined water tubes connected at their ends to uptake and downtake headers, respectively, the tubes being arranged in horizontal rows and the headers being spaced apart a distance at least as great as the diameter of a tube, a plurality of tubes in each row entering each header and the ends of the tubes being bent to space the tubes in each row uniformly across the boiler, the horizontal rows being arranged in pairs vertically with the vertical distance between adjacent pairs greater than the distance between the rows of a pair, each header having a handhole opposite the ends of the tubes of each pair of rows entering the header.
- 20 25. A water tube boiler, having horizontally inclined water tubes connected at their ends to uptake and downtake headers, respectively, the tubes being arranged in horizontal rows and the headers being spaced apart a distance at least as great as the diameter of a tube, a plurality of tubes in each row entering each header and the ends of the tubes being bent to space the tubes in each row uniformly across the boiler, the horizontal rows being arranged in pairs vertically with the vertical distance between adjacent pairs greater than the distance between the rows of a pair, each header having a handhole opposite the ends of the tubes of each pair of rows entering the header, some of said handholes being circular and the remainder elongated with the long axis vertical, each circular hole having an elongated hole adjacent it.
- 30 35. A water tube boiler having horizontally inclined water tubes connected at their ends to uptake and downtake headers, respectively, the downtake headers being formed in two parts with nipples connecting the parts, a transverse baffle extending across the tubes to give the gases an up-pass over one end of the tubes and a down-pass to the spaces between said nipples, said tubes being bent at their ends to enter said headers and the spaces in said baffle around the tubes being larger than the diameter of the tubes.
- 40 45. A water tube boiler, having horizontally inclined water tubes connected at their ends to uptake and downtake headers, respectively, the tubes being arranged in horizontal rows and the headers being spaced apart a distance at least as great as the diameter of a tube, a plurality of tubes in each row entering each header and the ends of the tubes being bent to space the tubes in each row uniformly across the boiler, the horizontal rows being arranged in pairs vertically with the vertical distance between adjacent pairs greater than the distance between the rows of a pair, each header having a handhole opposite the ends of the tubes of each pair of rows entering the header, some of said handholes being circular and the remainder elongated with the long axis vertical, each circular hole having an elongated hole adjacent it.
- 50 55. A water tube boiler having horizontally inclined water tubes connected at their ends to uptake and downtake headers, respectively, the headers being spaced apart a distance of at least a diameter of a water tube, and a closure for each of such spaces, comprising a metal plate having its edges contacting with and held against the walls of adjacent headers.
- 60 65. A water tube boiler, having horizontally inclined water tubes connected at their ends to uptake and downtake headers, respectively, the headers being spaced apart a distance of at least a diameter of a water tube, and a closure for each of such spaces, comprising a metal plate having its edges contacting with and held against the walls of adjacent headers, the plate having openings at spaced intervals to permit the insertion of cleaning tools, and closures for said openings.
- 70 75. A water tube boiler, having horizontally inclined water tubes connected at their ends to uptake and downtake headers, respectively, the headers being spaced apart a distance of at least a diameter of a water tube, and a closure for each of such spaces, comprising a metal plate extending across such space with its edges contacting with the walls of adjacent headers and the plate having portions inserted in vertical slits formed in projections on said headers.
- 80 85. A water tube boiler, having horizontally inclined water tubes connected at their ends to uptake and downtake headers, respectively, the headers being spaced apart a distance of at least a diameter of a water tube, and a closure for each of such spaces, comprising a metal plate extending across such space with its edges contacting with the walls of adjacent headers and the plate having relatively short projecting portions on each edge engaging a slit in a lug formed in a header.
- 90 95. A water tube boiler, having horizontally inclined water tubes connected at their ends to uptake and downtake headers, respectively, the headers being spaced apart a distance of at least a diameter of a water tube, and a closure for each of such spaces,

- comprising a plurality of metal plates each extending across such space with its edges contacting with the walls of adjacent headers and with the tops and bottoms of adjacent 5 plates overlapping, each plate having a pair of oppositely disposed projections on its edges, each engaging a slit in a lug formed on a header with such projections resting on the bottom of the slit.
- 10 20. A water tube boiler having adjacent sections, each section having water tubes connecting a pair of vertically extending rounded section headers, the adjacent headers being spaced apart sufficiently to allow 15 withdrawal of a section, the tube nest of each section being of greater width than the width of its header, the tubes in the sections being uniformly spaced from side to side of the boiler, and the tubes in the lower part of 20 the boiler being spaced apart a horizontal distance greater than the horizontal distance between tubes in the upper part thereof.
21. A water tube boiler having adjacent sections, each section having water tubes connecting a pair of vertically extending rounded section headers, the adjacent headers being spaced apart sufficiently to allow withdrawal of a section, the tube nest of each section being of greater width than the width 30 of its header, the tubes in the sections being uniformly spaced from side to side of the boiler, the tubes in the lower part of the boiler being spaced apart a horizontal distance greater than the horizontal distance 35 between tubes in the upper part thereof, and those in the lower part being of larger diameter than those in the upper part.
22. A water tube boiler having adjacent sections, each section having water tubes 40 connecting a pair of vertically extending rounded section headers, the adjacent headers being spaced apart sufficiently to allow withdrawal of a section, the tube nest of each section being of greater width than the width 45 of its header, and said headers having handholes affording access to the tubes, and the tubes being bent at their ends to point towards said handholes.
23. A water tube boiler having adjacent sections, each section having water tubes 50 connecting a pair of vertically extending rounded section headers, the adjacent headers being spaced apart sufficiently to allow withdrawal of a section, the tube nest of each section being of greater width than the width 55 of its header, and the tubes being staggered in the direction of gas flow.
24. In a heat transfer device, a plurality of sections arranged side by side, each section having a pair of headers provided with walls having sets of tube holes, tubes secured in said holes and connecting the two headers of each pair, at least some of said tubes being bent at their ends to enter the holes 60 in the header walls, the headers at each end of the sections having a series of longitudinally disposed openings giving access to the tubes, closures therefor, a water compartment common to a group of headers at one end of the sections, pipes connecting the end portions of said headers to said water compartment, means causing hot gases to flow across said tubes, the first tubes contacted by the gases being spaced relatively 70 widely in a direction transverse to the flow of gases, and the tubes contacted by the gases later being spaced relatively close together in said transverse direction.
25. In a heat transfer device, a plurality of sections arranged side by side, each section having a pair of headers provided with walls having sets of tube holes, tubes secured in said holes and connecting the two headers of each pair, at least some of said tubes being bent at their ends to enter the 75 holes in the header walls, the headers at each end of the sections having a series of longitudinally disposed openings giving access to the tubes, closures therefor, a water compartment common to a group of headers at one end of the sections, pipes connecting the end portions of said headers to said water compartment, and means causing hot gases to flow across said tubes, the first tubes contacted by the gases being of relatively large 80 diameter and spaced apart a greater distance than tubes later contacted.
26. A water tube boiler unit comprising a plurality of sections arranged side by side, each section having a pair of headers with longitudinally extending circumferentially curved wall portions provided with sets of holes each arranged in a circumferential band of said curved surface, tubes secured in said holes and connecting the two headers of each pair, at least some of said tubes being bent at their ends to enter the holes in the curved walls, the headers at each end of the sections having a longitudinally disposed series of 85 openings giving access to the tubes, closures therefor, a steam and water separator disposed above the level of one group of headers and arranged to have a water level intermediate thereof, and pipes connecting the end portions of both groups of headers to said 90 separator, the pipes connecting one group of headers to the separator being adapted to conduct fluid from the separator to the headers and the pipes connecting the other group of headers to the separator being adapted to conduct fluid to the separator.
27. A water tube boiler unit comprising a plurality of sections arranged side by side, each section having a pair of headers with longitudinally extending circumferentially curved wall portions provided with sets of holes each arranged in a circumferential band of said curved surface, tubes secured in said holes and connecting the two headers of each pair, at least some of said tubes being 100
- 105
- 110
- 115
- 120
- 125
- 130

bent at their ends to enter the holes in the curved walls, the headers at each end of the sections having a longitudinally disposed series of openings giving access to the tubes, closures therefor, a steam and water separator disposed above the level of one group of headers and arranged to have a water level intermediate thereof, and pipes connecting the end portions of both groups of headers to said separator, the pipes connecting one group of headers to the separator being adapted to conduct fluid from the separator to the headers and the pipes connecting the other group of headers to the separator being adapted to conduct fluid to the separator, the tubes in rows transverse to the headers being substantially uniformly spaced in said rows.

28. A water tube boiler unit comprising a plurality of sections arranged side by side, each section having a pair of headers with longitudinally extending circumferentially curved wall portions provided with sets of holes each arranged in a circumferential band of said curved surface, tubes secured in said holes and connecting the two headers of each pair, at least some of said tubes being bent at their ends to enter the holes in the curved walls, the headers at each end of the sections having a longitudinally disposed series of openings giving access to the tubes, closures therefor, a steam and water separator disposed above the level of one group of headers and arranged to have a water level intermediate thereof, and pipes connecting the end portions of both groups of headers to said separator, the pipes connecting one group of headers to the separator being adapted to conduct fluid from the separator to the headers and the pipes connecting the other group of headers to the separator being adapted to conduct fluid to the separator, the tube nest connecting each pair of headers being wider than the distance between center lines of adjacent headers.

29. A water tube boiler unit comprising a plurality of sections arranged side by side, each section having a pair of headers provided with walls having sets of tube holes, tubes secured in said holes and connecting the two headers of each pair, at least some of said tubes being bent at their ends to enter the holes in the header walls, the headers at each end of the sections having a longitudinally disposed series of openings giving access to the tubes, closures therefor, means causing hot gases to flow across said tubes, the spacing of said tubes being substantially uniform across the gas stream, a steam and water separator disposed above the level of one group of headers and arranged to have a water level intermediate thereof, pipes connecting the end portions of both groups of headers to said separator, the pipes connecting one group of headers to the separator being adapted to conduct fluid from the separator to the headers, and the pipes connecting the other group of

headers to the separator being adapted to conduct fluid to the separator.

30. A water tube boiler unit comprising a plurality of sections arranged side by side, each section having a pair of headers with longitudinally extending circumferentially curved wall portions provided with sets of holes each arranged in a circumferential band of said curved surface, tubes secured in said holes and connecting the two headers of each pair, at least some of said tubes being bent at their ends to enter the holes in the curved walls, the headers at each end of the sections having a longitudinally disposed series of openings giving access to the tubes, closures therefor, a steam and water separator disposed above the level of one group of headers and arranged to have a water level intermediate thereof, and pipes connecting the end portions of both groups of headers to said separator, the pipes connecting one group of headers to the separator being adapted to conduct fluid from the separator to the headers and the pipes connecting the other group of headers to the separator being adapted to conduct fluid to the separator, the tube nest connecting each pair of headers being wider than the distance between center lines of adjacent headers.

31. A water tube boiler unit comprising a plurality of sections arranged side by side, each section having a pair of headers formed of seamless tubes with longitudinally extending circumferentially curved wall portions provided with sets of holes each arranged in a circumferential band of said curved surface, water tubes secured in said holes and connecting the two headers of each pair, at least some of said tubes being bent at their ends to enter the holes in the curved walls, the headers at each end of the sections having a longitudinally disposed series of openings giving access to the tubes, closures therefor, a steam and water separator common to a group of headers at one end of the sections, and pipes connecting the end portions of said headers to said steam and water separator.

32. A water tube boiler unit comprising a plurality of sections arranged side by side, each section having a pair of headers formed of seamless tubes with longitudinally extending circumferentially curved wall portions provided with sets of holes each arranged in a circumferential band of said curved surface, water tubes secured in said holes and connecting the two headers of each pair, at least some of said tubes being bent at their ends to enter the holes in the curved walls, the headers at each end of the sections having a longitudinally disposed series of openings giving access to the tubes, closures therefor, a steam and water separator common to a group of headers at one end of the sections, and pipes connecting the end portions of said headers to said steam and water separator, each of

said headers having a section whose perimeter includes curves of different radii, the tubes entering the header along a surface having one of said radii and substantially 5 perpendicular thereto.

33. A water tube boiler unit comprising a group of uptake headers and a group of down-take headers, both having longitudinally extending circumferentially curved wall portions provided with sets of holes, each arranged in a circumferential band of said curved surface, tubes secured in said holes and connecting the uptake and downtake headers, at least some of said tubes being bent at 10 least one end to enter said holes, said headers having longitudinally disposed sets of openings giving access to the tubes, closures for said openings, a steam and water separator disposed above the level of one group of 15 headers and arranged to have a water level intermediate thereof, and pipes connecting the end portions of both groups of headers to said separator, the pipes connecting one group of headers to the separator being adapted to 20 conduct fluid from the separator to the headers and the pipes connecting the other group of headers to the separator being adapted to 25 conduct fluid to the separator.
